SIEMENS & HALSKE, A. G., OF SIEMENSSTADT, NEAR BERLIN, GERMANY, A COR-
PORATION OF GERMANY.

DISK-ENGINE.

1,182,033.

Specification of Letters Patent.

Patented May 9, 1916.

Application filed July 3, 1914. Serial No. 848,999.

To all whom it may concern:

Be it known that I, JOHAN MATHIAS KAREL PENNINK, a subject of the Queen of the Netherlands and residing at Amsterdam, 5 Netherlands, have invented certain new and useful Improvements in Disk-Engines, of which the following is a specification.

My invention relates to disk-engines of the type comprising a crank-disk operatively connected to a disk carried by a ball in the middle thereof and a primary object is to provide an improved engine of this type adapted to be employed as a motor, pump or meter, or as a machine for compressing gaseous or fluid media.

Known disk-engines comprising a crank-disk operatively connected to a rolling disk having a small ball in the middle thereof and a pin for guiding the disk and transmitting its motion have various defects attached to them. The pin of the ball frequently broke and fractures of the disk, generally made of ebonite, frequently occurred at the place where it had a radial incision 25 and embraced the partition in the working or metering chamber. Further, the accuracy of known water-meters of this type soon diminished in consequence of the wear of the pin of the ball and owing to the wear of the 30 guiding cones, because the rolling disk ceased to contact properly with the periphery of the working chamber and the measuring spaces were no longer kept tight.

According to my invention I increase the 35 strength of the ball and disk, care being taken that the weight of these parts is not too great, in order to enable the same to float in water if necessary.

In known disk-engines of the type described the rolling disk is displaced irregularly relatively to its conical guiding surfaces when the engine is running, and another object of my invention is to cause the displacement of the disk to be as regular as 45 possible.

Another object is to provide a materially better joint between the rolling disk and the cones than in known disk-engines of the type described.

Further objects are to provide a disk-engine of the type described of great stability adapted for measuring large quantities of a liquid medium and to provide improved means for lubricating the crank-disk.

Another object is to provide an improved

joint between the ball in the middle of the rolling disk and the partition extending in the working chamber into a recess or slot in the disk carried by the ball.

To these and other ends described herein-after my invention consists in the construction, arrangement and combination of parts described hereinafter and pointed out in the claims.

Several illustrative embodiments of the 65 invention in the form of water-meters are represented by way of example in the accompanying drawings, wherein:—

Figure 1 is a vertical section taken on the bent line I—II in Fig. 2 showing a small 70 water-meter, and Fig. 2 is a top plan view of the meter after the upper part thereof has been removed; Fig. 3 is a vertical section showing a modified form of meter comprising a toothed disk, and Fig. 4 is a like view 75 showing part of another form of meter comprising a modified toothed disk; Fig. 5 is a development of the cylindrical section taken on the line III—IV in Fig. 3, Fig. 6 shows the ball and disk according to Fig. 3, partly 80 in elevation and partly in section, Fig. 7 shows the same parts according to Fig. 4, and Fig. 7^a shows the same parts according to another form of the teeth on the disk; Fig. 8 is a vertical section of a larger type of 85 water-meter, Fig. 9 is a part section taken on the line V—VI in Fig. 8; Figs. 10 and 11 show two different forms of the joint between the working chamber and the crank-disk and, Fig. 12 is a top plan view of the 90 lower part of a modified form of water-meter having a toothed disk and comprising a second partition arranged diametrically opposite the customary partition.

Referring firstly to Figs. 1 and 2, this 95 form of my improved disk-engine or water-meter comprises a ball 1 which is hollow and is made of metal, *e. g.* copper or brass, and has a larger diameter than was customary heretofore. The disk 2, which may also 100 be hollow, is preferably made of two halves integral with the two halves of the ball, the two parts being pressed and then carefully tooled. Such a ball and disk are sufficiently strong and not too heavy. The 105 ball is provided at two diametrically opposite places with hemispherical recesses 3, into one of which is inserted a ball 4 which takes into a hemispherical socket or recess 5 in the crank-disk 6. The latter contacts 110

in the upper part 7 of the housing of the meter with that side of the ball 1 which faces the same, and the part of the housing containing the crank-disk is packed by suitable means between the ball 4 and the part 7. The crank-disk 6 is provided with several recesses 5. Such a crank-disk 6 which is mounted on the driving shaft 8 for the counting mechanism may be provided in 10 duplicate, *i. e.* one may be provided below the ball 1 in the lower part 9 of the housing if desired. As seen at the left-hand of these figures, a radial partition 11 is provided in the working chamber 10 of the 15 housing 7, 9 extending up to the face of the ball 1. This partition is embraced by the disk 2 which is recessed or slotted radially at this place, as clearly shown in Fig. 2, but the disk does not contact with the 20 partition. Diametrically opposite the middle of the recess or slot 12 in the disk 2 a pin 13 is fastened to the disk, and its projecting end takes into a groove 14 which runs parallel to the plane of the drawing 25 in Fig. 1 in the housing 7, 9. The disk 2 can thus rotate about the pin 13 and as it is clamped neither diametrically nor axially, it can roll freely and execute an oscillatory movement. In this manner contact of 30 the disk 2 with the partition wall 11 and, consequently, wear of these two parts is prevented.

The top 15 and bottom 16 of the housing 7, 9, built up of more than two parts if desired, are conical and limit the oscillation of the disk 2 upward and downward. When the disk is of large diameter packing *a* is 35 preferably provided for forming a tight joint between the crank-disk 6 and the metering chamber; additional packing *b* may be provided in the lower part 9 of the housing if desired.

The inlet *c* and the outlet *d* open into the working chamber 10 in the housing at 40 the two sides of the partition 11. Assuming that the disk 2 is located in the position shown in Fig. 1, so that it bears on the right-hand against the upper cone 15 and on the left-hand against the lower cone 16, the inlet *c* will be open and a rolling motion about the two cones will be imparted to the disk by the inflowing current of water. As the periphery of the disk is 45 always longer than the average length of the periphery of the cone, at each revolution a relative displacement of the two parts takes place. During the rolling in the first quadrant counting from the wall 11 the displacement of the disk increases from zero to a maximum, in the second quadrant it diminishes to zero, and in the third and fourth quadrants the same play is repeated. The 50 points of the disk located in the line passing through the guide pin 13 and the middle of the wall 11 move in one vertical plane

and have an oscillatory movement therein, and points located in lines at right angles thereto describe a closed path having the form of an 8.

As regards the movement of the disk 75 there is of course no difference between forward and backward, this being an advantage which makes itself felt particularly when erecting the apparatus in the line of pipes. In all the embodiments the water-meter is shown horizontal and provided with lateral pipes *c*, *d*. If desired, it may be arranged above these pipes, and when the water-meter has worked for a fairly long time in one direction it may be simply 80 turned around and worked in the opposite direction. Further, in consequence of the symmetrical shape of the disk on the ball this disk is reversible, so that, with regard to the wear of the balls 4 and their sockets 85 or recesses 5, eight different combinations are possible when the crank-disk 6 is provided with four recesses 5.

Fracture of the balls 4 is not to be feared 90 even when they are made very small, because they are stressed materially more favorably than in the case of pins employed heretofore. The defects formerly connected with the transmission of power are hereby 95 entirely obviated.

In the above-described embodiment comprising the pin 13 guided in the groove 14 the error due to the irregular displacement of the disk 2 when rolling is not entirely removed. For, as heretofore, the maximum displacement will occur in the plane passing through the center of the ball 1 and located at right angles to the plane passing through the wall 11 and the center of the disk. In two positions of 100 the disk there are always two points in this plane in which a maximum of resistance to displacement occurs, so that the ball and the conical guides are liable to be worn unevenly. These points are, as it were, 105 dead centers when the disk rolls.

In order that the total displacement of the disk may be distributed regularly as much as possible over its entire periphery, I provide the faces of the disk 2 and the conical faces 15, 16 with teeth 17 and 18, respectively, as shown in Figs. 3 to 8 and in Fig. 12. If these teeth have the shape of waves such that at the crest and in the hollow of each wave the teeth of the disk have a small amount of clearance in the waves of the conical faces (Fig. 5), then the total displacement is distributed over the entire periphery. The total of the partial displacements should be equal to the total displacement. 110

The views of the teeth shown in Figs. 6 and 7 show that the lower and upper teeth of the disk are displaced half the pitch relatively to one another. This displacement 115

of the teeth is necessary because, when the disk moves, rotation is to take place each time about a constantly progressing instantaneous axis, and these instantaneous axes must be generating lines of the original conical surfaces, in order that steady running may result. It will also be evident from an inspection of Fig. 5, that the teeth 17 on either side of the disk are of greater pitch than the teeth 18 on the cones over which the opposite faces of said disk are moved. In consequence of these teeth the movement of the disk is perfectly positive and in this manner I obtain the advantage that a materially better joint is made between the disk and the cones. The cause of the moving parts wearing unevenly is removed, and there is much less danger of these parts fracturing than in water-meters of the type described as known heretofore. When the speed of the meter is low and when the quantities of fluid to be metered are small the teeth will constitute a kind of labyrinth packing (Fig. 5) whereby greater accuracy of measurement is assured in this case, while the joint is always good at high speeds.

If desired, the teeth 17 of the disk 2 or the teeth 18 of the cones 15, 16 of the housing 7, 9 need extend over only a small part of the breadth of the disk and cones, as shown at 17¹ and 18¹ in Figs. 4, 7 and 8. Obviously, in all forms of meter having teeth as described above the guide pin 13 will be omitted.

The right-hand part of Fig. 7 shows a modification in which the teeth consist of strips of metal 19 of suitable shape suitably attached to the disk 2. The teeth of the conical surfaces may be formed in like manner if desired. In this construction the strength and the elasticity of the disk is increased, and repairs can be made if the teeth are injured.

In order to prevent wear, the teeth of the disk and those of the conical surfaces may be provided with exchangeable points 20, as shown in Fig. 5, the same being inserted by means of dovetailed joints or in other suitable manner.

When large quantities of water are to be measured it is very important that the water-meter be exceedingly stable. The crank-disk will require to be lubricated, which is preferably effected with water when the meter is connected in water-pipes. The form of water-meter shown in Figs. 8 and 9 meets these requirements. Instead of the driving ball 4 this meter comprises a pivot pin 21 which is integral with the crank-disk 6; this pin may be cylindrical or conical and is journaled in a recess 23, preferably lined with white metal 22, in the hollow ball 1. For forming a tight joint between the working chamber and the crank-

disk packing 24 of metal or leather is used; similar packing 25 may be provided, in addition, above the crank-disk 6. The holes 26 which are made in the wall of the housing, the crank-disk and the cone and which are supplied with water under pressure at 26¹ provide that the crank-disk moves in a chamber in which a pressure exists which is slightly greater than that in the working chamber 10. The packing 24 and 25 is subjected to this higher pressure and consequently the moving parts are well packed.

When the ball 1 is of large dimensions attention must be paid to the joint between the partition 11 and the ball 1. In small water-meters this is not so important. In the meter shown in Figs. 8 and 9 a good joint is formed by making the partition 11 hollow and inserting into it a plate 27 which has its inner end cut to a suitable curve and is pressed by a suitable pressure against the ball 1; in this arrangement the frictional resistances need not be materially increased.

Under certain circumstances it may be preferable to pack the joint between the working chamber 10 and the chamber containing the crank-disk not by leather collars 24, but by slit rings 28 which are inserted like elastic piston-rings into suitable grooves cut to receive them, as shown in Figs. 10 and 11. Such packing between the working chamber 10 and the crank-disk 6 arranged in any of the ways described above enable the crank to be lubricated with oil. The entrance of lubricating oil into the metering chamber is sufficiently prevented in this manner.

Particularly the packing shown in Figs. 8 and 9 renders the herein-described disk-engine or water-meter adapted for metering or for being driven by, gases of any desired temperature, if the gas is at a sufficient pressure and if a small loss of pressure is allowed. This construction also admits of additional packing at the periphery of the disk, as shown in Fig. 8, in the form of a piston-ring 29.

At first, when the teeth of the disk and the conical surfaces do not bear against one another, the meter is by no means tight, but as soon as the movement of the water is so powerful that the disk begins to roll one or more of the teeth on the two parts contact with one another (Fig. 5), because during the rolling motion the disk tends to lag behind, and as soon as the disk moves leakage is stopped and the water-meter accurately measures the quantity of water passing through it.

In order to make the water-meter water-tight at the beginning of the metering operation the ball 1 may be provided with a suitable spring 30, e. g. a leaf-spring, which bears against the partition 11, as shown in Fig. 12. The disk is thereby constantly

pressed to the left, so that at least one tooth of the disk always bears against one tooth on the conical surface and forms a tight joint, so that the rolling movement of the disk 5 begin immediately the water is turned on.

When the movement of the disk is very rapid, as is the case particularly in currents of gas, the unsymmetrical shape of the disk 10 is a defect. This can be remedied in a simple manner by arranging a second partition 31 on the side diametrically opposite the partition 11. The disk 2 will then have on this side a second recess or slot 32 similar to the recess or slot 12 on the left. The same 15 need not be so broad however. The current of gas is led through a side channel 33 around the wall 31. In this arrangement the disk 2 is perfectly balanced.

As a water-meter made in the above-described manner is no longer dependent in its action with regard to accuracy of movement and measurement on the speed, its range of measurement is considerably greater than that of forms known heretofore. 20 Consequently, the number of sizes in which the ordinary disk water-meter are generally made at the present day can be considerably reduced, so that water boards, engineers, plumbers and others do not require to keep 25 such a large number of apparatus and spare parts as heretofore.

As the herein-described water-meters work much more regularly and more exactly than those known heretofore calibration and testing is considerably simplified. Further, in consequence of fewer repairs the life of the water-meter is materially increased and owing to the simplification of the water 35 service a considerable saving is obtained.

It may be mentioned, in addition, that the play provided in the teeth admits of the passage through the water-meter of grains of sand and the like carried along by the current of water without the accuracy of 40 measurement being impaired in the slightest and without any injury of the water having to be feared.

Instead of being used as a water-meter the described disk-engine can be employed for

measuring any other liquid. *e. g.* oils, petroleum and the like, and also gases.

The described engine can also be employed as a pump when it is driven. If the joint formed by the teeth admits of large differences of pressure the machine can also 55 be employed as a reversible engine driven by compressed gas, steam or the like. Another sphere of employment for the described machine is that of a fan. In all the modes of employment several machines may 60 be connected in series or in parallel in order to work as compound pumps, motors, fans or the like.

I claim:—

1. In a disk engine, the combination with 65 a casing having upper and lower toothed conical guiding surfaces, of an equatorial disk having teeth on opposite sides thereof in mesh with said toothed guiding surfaces, the teeth in each of said conical guiding 70 surfaces being of different pitch than the teeth on that side of the equatorial disk which meshes therewith.

2. In a disk engine the combination with 75 the casing having upper and lower toothed conical guiding surfaces, of an equatorial disk having on the two sides the same number of teeth as the conical surfaces, the teeth of these latter and of the disk being however of different pitch.

3. In a disk engine, the combination with 80 a casing having oppositely disposed toothed conical guiding surfaces, of an equatorial disk having teeth on opposite faces thereof meshing respectively with said toothed guiding surfaces, the teeth on each face of said equatorial disk being displaced circumferentially with respect to the teeth on the opposite face of said disk and the pitch of the teeth on each face of said disk being different from the pitch of the teeth with which they mesh.

In testimony whereof, I affix my signature in the presence of two witnesses.

JOHAN MATHIAS KAREL PENNINK.
